CONTROL DEVICE FOR OUTBOARD MOTORS

Howarth P. Henry, Englishtown, N. J.

Application December 4, 1951, Serial No. 259,753

5 Claims. (Cl. 115—18)

The present invention relates to novel and useful improvements in devices for controlling the direction (forward or reverse) in which a boat is propelled by a motor and it relates, more particularly, to a control device for attachment to an outboard motor.

An object of the present invention is to provide a simple and inexpensive control device which is particularly adapted for attachment to an outboard motor to control the direction (forward or reverse) in which a boat will be driven by the motor. A control device embodying the present invention does not involve the use of gears or any alteration of the working parts of the motor and its operation is entirely automatic.

Other objects and advantages of the present invention will be apparent and best understood from the following description and the accompanying drawings in which:

Fig. 1 is a side view of a control device embodying the present invention as attached to an outboard motor;

Fig. 2 is a rear view of the control device shown in Fig. 1;

Fig. 3 is a section view taken along the line 3—3 of Fig. 1;

Fig. 4 is a section view taken along the line 4—4 of Fig. 2;

Fig. 5 is a section view taken along the line 5—5 of Fig. 3;

Fig. 6 is a section view taken along the line 6—6 of Fig. 3;

Figs. 7 and 8 are side views of the control device shown in Fig. 1 with the parts in different operating positions thereof; and

Fig. 9 is a graph schematically illustrating the operating characteristics of a control device such as illustrated in Fig. 1.

Referring to the drawings in detail, the lower portion of a conventional outboard motor is illustrated and this portion includes a drive shaft housing 10 which has a propeller 11 located at its lower end beneath an anti-cavitation and exhaust plate 12.

A bracket 13 has portions located on opposite sides of the shaft housing 10 and is detachably clamped thereto by means of a nut and bolt 14. The bracket 13 has two oppositely disposed arms 15 which extend rearwardly of the shaft housing 10 to a point above the propeller 11. The arms 15 have aligned openings therein through which a shaft 16 extends and is thus supported by the arms. A control plate 17 is supported on the shaft 16 and is movable about the shaft from a vertical position to a horizontal position with stops limiting its movement to an arc of about 120 degrees. The 120-degree movement of the plate is provided to allow for an angular position of the shaft housing 10 when the motor is installed on a boat.

When the control plate 17 is in vertical position, it extends downwardly around the anti-cavitation and exhaust plate 12 of the motor and the lower portion of the plate is located immediately in back of the pro-

peller 11 in fairly close proximity thereto and is of sufficient size to oppose the effective area of the propeller's action. The portion of the control plate 17 opposite to the propeller 11 is curved in a vertical plane and has a generally concave surface with the plate partially enclosing the propeller at the sides thereof. The bottom end of the plate is flat, as indicated at 18, to provide a surface on which the plate can plane when it is in its horizontal position as shown in Fig. 8.

10 The control plate 17 is normally held in its vertical position by a pair of coil springs 19 and 19'. The coil springs 19 and 19' are connected to the plate 17 by eye-bolts 20 and to ears 21 extending from the bracket 13. Concentrically arranged within the coil springs 19 and 19', respectively, there are supplemental coil springs 22 and 23. Plungers 24 are slidably fitted within the supplemental springs 22 and 23 and are connected to the eye-bolts 20 on the plate 17. The ends of the plungers 24 have headed portions 25 which engage with the ends of the supplemental springs 22 and 23 and thus, bring the supplemental springs into action in addition to the main springs 19 and 19' as the plate 17 swings from its vertical or down position to its horizontal or up position. For purposes described hereinafter, the supplemental springs 22 and 23 are of different lengths and thus, come into action at different points in the movement of the control plate.

30 The ears 21 on the bracket 13 to which the coil springs acting on the plate are connected are so located with respect to the shaft 16 on which the plate is supported that the moment arm of the forces of the springs acting on the plate decreases as the plate 17 swings upwardly. Just prior to the plate reaching its horizontal position, the springs 19 and 19' strike stops 26 on the bracket 13 and are bent slightly out of their normal line of action as indicated in Fig. 8. In this position, the moment arm of the force exerted by the springs on the plate is very small so that a very slight downward pull is exerted on the plate. Thus, the plate 17 will be held in its horizontal position with relatively small forces acting on it in opposition to the springs and in this position, the flat trailing edge 18 at the bottom of the plate will in effect provide a planing surface for the plate so that there will be a very small drag on the boat.

45 The operation of the attachment described above will be described with particular reference to Fig. 9. When the motor is started, the springs 19 and 19' hold the plate 17 down or in vertical position and the action of the water being forced against the plate 17 by the propeller causes the boat to move backward or in reverse. 50 The principle of this operation has been known and utilized in the Kitchen rudder. As the speed of the propeller is increased, the plate automatically raises and when the plate reaches an angle of from 20 to 25 degrees, the boat will remain stationary or be in neutral. The first or shorter supplemental spring 23 comes into action at this position of the plate 17 and has the effect of holding the plate in this position over a range of propeller speeds as represented by the portion of the curve of Fig. 9 indicated at A.

60 When the propeller speed is increased sufficiently to raise the plate still further, the boat will start moving forward and when the plate 17 has reached an angle of approximately 40 degrees, the second supplemental spring 22 comes into action and serves to maintain the plate at this position regardless of slight changes in propeller speed as represented by the portion of the curve of Fig. 9 indicated at B. Thus, at the 40-degree position of the plate, forward movement of the boat at a low speed suitable for trolling is maintained over a range of propeller speeds. When the speed of the propeller is increased further, the plate 17 then raises quickly to its horizontal

position, but due to the changing moment arm of the springs, the forces acting on the plate 17 decrease to a minimum when the plate is horizontal and the boat is moving at full speed ahead.

As will be seen from the foregoing, the supplemental springs 22 and 23 each come into action at different times and they maintain the plate in its neutral and trolling positions over a range of motor speeds so that the manipulation of the motor speed is not critical. Also, it will be seen that the operation of the present control device is entirely automatic depending entirely on the speed at which the motor drives the propeller.

It will be understood that the angular position of the plate at which the boat stands still or moves forward at trolling speed may vary somewhat depending on the size of the plate and the action of the particular propeller which it opposes. However, such positions may be readily ascertained for a given set of conditions and the action of the supplemental springs may be provided for accordingly.

It will also be understood that various modifications and changes may be made in the embodiment of the invention illustrated and described herein without departing from the scope of the invention as defined by the following claims.

I claim:

1. In a device for automatically controlling the direction in which a boat is propelled by a motor-driven propeller, the combination comprising a support, said support being located above a propeller, a plate, means pivotally mounting the plate on the support at a point above the propeller, said plate having a portion extending downwardly from the support and opposing the thrust of the propeller and being movable about its pivot point from said downwardly extending position to a generally horizontal position, the portion of the plate opposing the propeller having a curved surface partially enclosing the propeller, spring means for automatically controlling pivotal movement of the plate, said spring means including a tension spring having one end thereof connected to the plate at a point located beneath the pivot point and having its other end connected to the support at a point spaced from the pivot point of the plate, said spring normally acting to hold the plate in its downwardly extending position, said locations of said points of connection providing a shortened line of action of the spring as the plate moves from its downwardly extending position towards its horizontal position and fulcrum means positioned in the path of travel of the spring, said fulcrum means engaging with the spring at a point intermediate its ends when the spring reaches the dead center position in movement of the plate toward its horizontal position.

2. In a device for automatically controlling the direction in which a boat is propelled by a motor-driven propeller, the combination as defined in claim 1 which includes a supplemental spring having one end connected to the support adjacent said point of connection of the first-mentioned tension spring therewith, and means connected to the plate adjacent the point of connection of the first-mentioned tension spring and said plate, said means being slidably movable into engagement with said supplemental spring upon a predetermined angular movement of the plate from its downwardly extending position towards its horizontal position and thereby enhancing the resistance of the first-mentioned tension spring.

3. In a device for automatically controlling the direction in which a boat is propelled by a motor-driven propeller of the type wherein a control plate is pivotally mounted on a support at a point above a propeller and has a downwardly extending portion located behind the propeller, said plate being pivotally movable through an arc of at least 90 degrees from a downwardly extending position to a horizontal position, characterized by the combination with said control plate of spring means for automatically controlling pivotal movement of the con-

trol plate, said spring means including a pair of tension springs connected between the plate and the support, each of said springs having one end thereof connected to the plate at a point beneath the pivot point of the plate and the other end thereof connected to the support at a point spaced from the pivot point of the plate, the connection points of the springs to the plate and the support being so located that the perpendicular distance from the pivot point of the plate to the line of action of the spring decreases as the plate moves from its downwardly extending position to a horizontal position and the springs occupy a substantially dead center position with respect to the pivot point of the plate when the plate is in its horizontal position, and fulcrum means positioned in the path of travel of the spring, said fulcrum means engaging with the springs at a point intermediate their ends when the springs reach said dead center position.

4. In a device for automatically controlling the direction in which a boat is propelled by a motor-driven propeller of the type wherein a control plate is pivotally mounted on a support at a point above a propeller and has a downwardly extending portion located behind the propeller, said plate being pivotally movable through an arc of at least 90 degrees from a downwardly extending position to a horizontal position, characterized by the combination with said control plate of spring means for automatically controlling pivotal movement of the control plate, said spring means including a pair of tension springs connected between the plate and the support, each of said springs having one end thereof connected to the plate at a point beneath the pivot point of the plate and the other end thereof connected to the support at a point spaced from the pivot point of the plate, the connection points of the springs to the plate and the support being so located that the perpendicular distance from the pivot point of the plate to the line of action of the springs decreases as the plate moves from its downwardly extending position to a horizontal position and the springs occupy a substantially dead center position with respect to the pivot point of the plate when the plate is in its horizontal position, fulcrum means located in the path of travel of the springs, said fulcrum means engaging with the springs intermediate their ends when the springs reach said dead center position, a pair of supplemental springs, one of said supplemental springs being associated with each of said tension springs and having one end thereof connected to the support at the point adjacent the connection of the associated tension spring thereto, and means connected to the plate for engaging with said supplemental springs upon angular movement of the plate from its downwardly extending position toward its horizontal position, said engaging means including members connected to the plate adjacent the connections of the tension springs thereto, said members being slidably movable into engagement with the supplemental springs.

5. In a device for automatically controlling the direction in which a boat is propelled by a motor-driven propeller, the combination as defined in claim 4 wherein the supplemental springs are located within the first-mentioned tension springs and the members engaging with the supplemental springs engage with the respective springs at different angular positions of the control plate.
